UNITED STATES PATENT OFFICE.

ABIJAH WALLACE, OF STROUDSBURG, PENNSYLVANIA, ASSIGNOR OF TWO-THIRDS TO MEYER DITTENHOFER, OF NEW YORK, N. Y.

DESIGN FOR THE BACK OF A COMB.

SPECIFICATION forming part of Design No. 19,124, dated May 28, 1889.

Application filed April 25, 1889. Serial No. 308,620. Term of patent 3½ years.

To all whom it may concern:

Be it known that I, ABIJAH WALLACE, a citizen of the United States, residing at Stroudsburg, in the county of Monroe and State of Pennsylvania, have invented and produced a new and original Design for the Backs of Combs; and I do declare the following to be a full, clear, and exact description of the same, reference being had to the accompanying drawing, forming a part thereof, in which a side view of the comb is represented.

The leading feature of my design consists in the representation of two nude or semi-nude human figures in reversed position produced in relief upon the back of the comb. From substantially the median line of the bodies forming the back of the comb the teeth of the comb project. The figures are disposed lengthwise of the comb.

In the accompanying drawing, *a* is the back of the comb, showing the two human figures in relief and in reversed position, and *b* are the teeth of the comb.

I claim—

The design for the backs of combs and like articles herein shown and described, the same consisting in the outline and conformation of two human figures in reversed position disposed lengthwise on the back of the comb, substantially as set forth.

In testimony whereof I affix my signature in presence of two witnesses.

ABIJAH WALLACE.
